UNITED STATES PATENT OFFICE.

CHARLES R. WATSON, OF NEW YORK, N. Y.

UNDERGARMENT AND METHOD FOR PRODUCING SAME.

1,258,836.

Specification of Letters Patent. Patented Mar. 12, 1918.

Application filed August 29, 1916. Serial No. 117,415.

To all whom it may concern:

Be it known that I, CHARLES R. WATSON, citizen of the United States, residing in the borough of Manhattan, city, county, and State of New York, have invented a new and useful Improvement in Undergarments and Methods for Producing Same, of which the following is a description.

This invention has reference to undergarments and particularly to "combination" undergarments for men's wear, and to the method for making same.

Among the objects of my invention may be noted the following: to provide a method for making combination garments from either a single tube of knitted fabric, or from a plurality of tubes of knitted fabric, or from a blank of knitted fabric or woven fabric, and to provide a one-piece garment having certain novel characteristics and functions.

With the above objects in view and others which will be detailed during the course of this description, my invention consists in the parts, features, elements and combinations thereof hereinafter described and claimed.

In order that my invention may be clearly understood, I have provided drawings wherein:

30 Figure 1 is a plan of a section of a single tube of knitted fabric from which my garment may be made;

35 Fig. 2 is a plan view illustrating the method of laying out and cutting the single tube of knitted fabric to make a garment according to my invention;

40 Fig. 3 is a front elevation of the garment-form after it has been cut from the single tube of knitted fabric and the garment-form folded to produce the completed garment;

45 Fig. 4 is a front elevation of the completed garment which may be made from a single tube of knitted fabric, from two tubes of knitted fabric, or from a flat blank of knitted or woven fabric;

Fig. 5 illustrates the method of producing the garment of Fig. 4 from two tubes of knitted fabric;

50 Fig. 6 is a view similar to Fig. 3, showing a garment-form made according to the method of Fig. 5 and;

Fig. 7 is a view illustrating the manner in which a garment-form may be cut from a blank of either knitted or woven fabric;

55 Referring to the drawings, Fig. 1 illustrates a section of a tube of knitted fabric,

the same being indicated by 1. The dotted lines 2 indicate the manner in which the tube will be cut to produce the unit sections 3 from which a garment-form will be cut. Fig. 1, shows the tube very much smaller than natural size.

In Fig. 2, one of the unit sections 3 is shown as treated by cutting off a corner along the line 4; cutting off the bottom of the tube on the line 5; cutting off one side of the tube on the line 6 and the continuation line 7; cutting off a curved section on the line 8, and another curved section on the line 9; and cutting off the top of the tube on the line 10. An incision is also made in the top of the tube on the two curved lines 11. The blank form thus made, is folded out flat and the two outer sections 12, are folded on the lines 13 with the edges 7 slightly overlapping, as along the line 14, said overlapping portion becoming the placket of the garment which may be open from the neck of the crotch. The fold-lines 13 become the sides of the garment. The oval incisions 11, become the arm-holes 15 of the garment and the top portions 10 become the back of the shoulders 16, the fronts of which are the top portions of the sections 12, said top portions being stitched to the tops 10 of the back section 17. An edge 6 is then stitched to an edge 4 up to the crotch 18, thus making the legs of the garment. Of course, sleeves may be added to the arm-holes 15 if desired.

Now, viewing Fig. 4, it will be understood that the edges of the placket opening, from the neck to the crotch 18, will be turned in or hemmed in any suitable manner to provide the finished placket 19 to the lower flap of which buttons 20 may be attached, while the top flap of the placket may have a tape of non-elastic material hemmed therein, in order to give stability to the button-holes and prevent the latter from unduly stretching. The arm-holes, the neck opening and the bottoms of the legs may all be hemmed and stitched ornamenteally, as at 21, in order to provide the proper finish. The line of stitching which produces the legs of the garment, is indicated at 22.

When this garment is made of knitted fabric, one of its essential characteristics is that its elasticity is transversely of the garment instead of longitudinally thereof, this being accomplished by knitting the tube with the wales longitudinally thereof. This

enables the legs of the garment to be stretched laterally extraordinarily for use, as will be readily understood. If the garment is made of woven fabric, it will be of sufficient dimensions below the waist and across the legs to enable the latter to be drawn aside for use. Therefore, another essential characteristic of the garment is that it is considerably narrower from the waist 10 up than from the waist down, the narrowing of the garment being rather abrupt, so as to produce the athletic form of upper or shirt portion, of the garment across the chest and shoulders.

15 In cutting the garment-form as above described, it is immaterial which portion is cut first, or what order of cutting may be followed; but, a single die cutter may be employed to cut out the garment-forms at a 20 single operation and in great numbers, or a band-cutter, or other form of cutter, may be employed to follow the pattern-lines in a manner well understood in the art.

If the garment be made of two tubular 25 sections of knitted fabric such as 3, assuming them to be substantial one-half the width of the tube out of which the garment-forms of Figs. 2 and 3 are cut, two sections of the tubular knitted fabric, such as 3, will 30 be superposed as shown in Fig. 5. The said two tubes will then be simultaneously cut obliquely lengthwise thereof, along the line 23. The left edge of the tubes will be cut along the curved line 24, to form the arm-holes. The top of the tubes will be cut on 35 the straight line 25, and on the curved line 26. The upper tube will have its upper layer and the bottom tube will have its lower layer cut on the line 27. The two garment-forms thus produced, are then laid with 40 their side cut edges edge-to-edge, as shown in Fig. 3, the fold-edges 28, becoming the opposite sides of the garment, and the shorter, cut, side edges becoming the placket 45 flaps 29, while the longer, cut, side edges are stitched together, to form the back seam of the garment. The cut edges 25, are then connected together to form the shoulders 30 of the garment, and the openings cut along 50 the lines 24, become the arm-holes 31, see Fig. 6. The legs of the garment are seamless, because the tube at that portion from the point 32, Fig. 5, to the bottom thereof, 55 has not been cut. The garment is then hemmed, bound, button-holed and buttoned as in Fig. 4, the only other difference between the garment made according to the two methods, being that the back of the garment according to the second method is 60 seamed while the other is seamless.

If a garment is made from a flat blank of either knitted or woven fabric, it may be cut from a rectangular blank of material according to the outlines shown in Fig. 7. In 65 this figure, after the blank of the form

shown is produced, either by a single stroke of a die or in any other manner found suitable and economical, the blank will be folded on the lines 33, thus bringing the opposite edges 34 into position to form the 70 front placket opening. The edges 35, are then stitched to the edges 36 respectively, so as to form the legs of the garment, the placket extending from the crotch 37, to the neck of the garment. The edges 38 are then 75 stitched together to make the shoulder straps. The arm-holes 39 are formed by cutting on the curved line 40. This garment may be hemmed, ornamented, bound, button-holed and buttoned in precisely the manner 80 of the other garments, as shown in Fig. 4. The garment-form of Fig. 7, may also be made from a flat blank of woven or knitted material, by first folding the same on the median line 41. Then a single die may cut 85 the edges 34, 35, 36, 38, and 39 to make the arm-holes 40, as previously described. The garment-form thus made will then be laid out flat and folded as above described on the lines 33, for the purpose of seaming and 90 finishing.

Obviously, in producing the garment-forms of Figs. 6 and 7, a single die may be employed and stacks of the tubes or rectangular fabric sections can be cut thereby at 95 a single operation, excepting that, in the form of Fig. 5, the sections cut away on the lines 27 would require a subsequent operation.

Having thus described my invention, what 100 I claim and desire to secure by Letters Patent is:

1. The method for making garments comprising cutting, from a single tubular section of knitted fabric of predetermined 105 length, a complete one-piece garment-form of predetermined shape; juxtaposing certain of the cut edges to form a wholly closed and seamless garment-back and a front placket open from the neck toward the crotch of the 110 garment; stitching other cut edges together to form abnormally wide and short leg portions, narrow shoulder pieces, neck-opening and arm-holes; and finishing the garment by 115 hemming or binding all free edges.

2. The method for making garments comprising cutting from suitable material a garment-form which is very wide at one end, and very narrow at the other end, and which has the characteristic outlines of the garment to be produced therefrom; juxtaposing cut edges of the garment-form, to provide a front placket open through the neck opening toward the crotch of the garment; stitching other cut edges together, to form abnormally 125 wide and short leg portions, narrow shoulder pieces, neck-opening and arm-holes; and finishing the garment by hemming all free edges.

3. A combination garment formed of a 130

single piece of material, having its lower end formed into abnormally wide and short leg portions and its upper end formed into a body portion having arm holes and neck opening, said garment also having its entire back closed from the neck opening to and through the crotch, and a front placket extending through the neck opening and downward toward the crotch.

10 4. A combination garment formed with a

body portion having neck and arm openings, and but one body opening providing a front placket extending through the neck opening toward the crotch, said garment being also provided at its lower end with abnormally wide and short leg portions and at its upper end with a comparatively narrow shoulder and chest portion. 15

CHARLES R. WATSON.
